(57) **CLAIM**

The ornamental design of an animal brush, as shown and described.

DESCRIPTION

FIG. 1 is a bottom perspective view of an animal brush showing our new design;

FIG. 2 is a top plan view thereof;

FIG. 3 is a bottom plan view thereof;

FIG. 4 is a side elevational view thereof;

FIG. 5 is a side elevational view thereof, opposite of FIG. 4; FIG. 6 is a front end elevational view thereof; and,

FIG. 7 is a rear end elevational view thereof.

The broken lines shown in the drawings are for illustrative purposes only and forms no part of the claimed design.
